VAPOR SEPARATION UNITS FOR INTERNAL COMBUSTION ENGINES

Roy L. Bowers, Flint, Mich., assignor to General Motors Corporation, Detroit, Mich., a corporation of Delaware
Filed Mar. 17, 1958, Ser. No. 721,982
1 Claim. (Cl. 183—2.5)

This invention relates to fuel systems and more particularly to units in liquid fuel systems for providing vapor-free fuel to internal combustion engines.

It has long been recognized that the presence of vapor in an engine feed line reduces and often eliminates the proper and effective functioning of the fuel pump and the engine. Vapor lock conditions in automotive gasoline feed systems arise because of use in rarefied atmosphere, use under elevated temperature conditions, high volatility characteristics of the particular fuel or from combinations of these circumstances.

The object of the present invention is to provide a unit for a liquid fuel system for an internal combustion engine which unit is low in cost, simple and compact in structure and highly effective in removing vapor from an engine fuel feed line.

A feature of the present invention is a liquid fuel system unit comprising a closed receptacle adapted to be incorporated in a fuel feed line, the receptacle having separate upper chambers, one of which is vented back to a liquid fuel supply reservoir. Another feature is a closed receptacle in which separate upper chambers are arranged to promote the separation of vapor from liquid fuel with the aid of a filtering element. Another feature is a closed receptacle having a depending wall enlarging the potential capability of the receptacle for separating vapor from liquid fuel as the latter flows through the receptacle. Another feature pertains to an annular filter element in a vapor separating closed receptacle which element is arranged to retain impurities while aiding to separate the vapor. Still another feature is a cup-shaped filter element which impedes the flow of impurities and promotes their precipitation into the lower portion of a receptacle for convenient and periodic removal from a liquid fuel system.

These and other important features of the invention will now be described in detail in the specification and claim.

In the drawings:

FIG. 1 is a partially diagrammatic view of a liquid fuel system for an internal combustion engine, one principal element being drawn partially in section as seen looking in the direction of the arrows 1—1 in FIG. 2 and presented to an enlarged scale as compared with other elements of the system;

FIG. 2 is a plane view of the principal element or unit shown in FIG. 1 and portions thereof being broken away better to illustrate the construction; and

FIG. 3 is a view in elevation of a portion of an element similar to that shown in FIGS. 1 and 2 representing a modified construction with parts broken away.

The fuel system, as depicted in FIG. 1 of the drawings, comprises a fuel supply reservoir or tank 10, a closed receptacle indicated generally at 14 and a fuel pump 16. An upper portion of the receptacle 14 is in the form of a casting 18 which defines an inlet chamber 22 with a zone of arcuate or U-shaped configuration and an L-shaped chamber 26 for the discharge of fuel. A boss 24 is formed on the upper portion 18 and is recessed threaded to receive a vent line 28 which connects the chamber 22 with a lower zone of the fuel tank. An orifice 29 is formed in the body of the casting 18 to give a restricted passage to the vent line 28. A port 30 is formed in the casting 18 and serves as a

2

means of communication between an inlet conduit 32 and the arcuate chamber 22. The other end of the conduit 32 is connected to the discharge side of the fuel pump 16 and the inlet side of the latter is connected by a conduit 34 to a bottom zone of the tank 10. A horizontal leg of the L-shaped outlet chamber 26 is connected by means of a conduit 36 to the fuel system of the engine being served.

A lower portion of the closed receptacle 14 comprises a transparent glass bowl 40, the rim of which is tightly held to the upper portion 18 with a sealing gasket 42 interposed. The bowl 40 is held in position by means of a conventional bail 44 which is generally U-shaped in configuration and having its upper ends 46 and 48 bent inwardly for pivoting in recesses formed in the casting 18. Compression of the gasket 42 to insure a tight seal may be affected by means of a screw adjustment arrangement 46 associated with the bail 44.

A vertical passage 49 forming one leg of the outlet chamber 26 is defined by a depending, substantially cylindrical wall or sleeve 50 which is surrounded by an annular shoulder 52 formed on the casting 18. The inlet chamber 22 substantially surrounds the outlet chamber 26 and extends above the sleeve 50.

An annular filter element generally indicated at 54 is located within the bowl 40 and comprises a fibrous filter element wall 56 of such porosity as to permit the passage of liquid fuel and restrict the passage of impurities. The porous material in the wall 56 may be accreted or woven as in conventional liquid fuel filtration usage. The filter element wall 56 is in the form of an annular trough, the upper interior margins of which are tightly held to an annular trough portion 58 formed in a metal disc 60. The peripheral margin of the disc is tightly held in position against a shoulder 61 of the casting 18 by means of the inner marginal periphery of the gasket 42. The center of the disc 60 is apertured to receive the sleeve or depending substantially cylindrical wall 50 and a sealing gasket 62 is interposed between the plate or disc 60 and the shoulder 52 to form a fluid tight seal. An annular series of openings 63 are formed in the disc 60 to convey fuel into the filter element.

It will be noted that the intake lines 34 and 32 considered with the pump 16 and also the discharge or outlet conduit 36 leading to the engine constitute means of relatively large flow capacity as compared with the vent means leading back to the tank 10.

In operation of the system depicted in FIG. 1, the fuel is directed by the pump 16 to flow through the lines 34 and 32 to the chamber 22. This chamber is of such size, particularly when assisted by the baffle action of the depending sleeve or wall 50, as to insure the separation of any vapor present from the liquid fuel before the fuel reaches the bottom end of the passage 49. A further assurance that the vapor separates and is not passed along with the liquid fuel is given by the baffle action and location of the filter element 54 transverse to the liquid fuel path at the zone where the separation is desired. The vapor separated in the chamber 22 will rise therefrom through the vent means which comprises the restrictive orifice 29 and the line 28. This vapor will be discharged into the tank 10 and be condensed as will be understood. Any air which may be present in the vapor will be vented from the tank 10 in a conventional manner as by way of the tank filler cap. Liquid fuel clarified by the filter material 56 passes downwardly into the bowl 40, then upwardly through the passage 49 and the outlet chamber 26 and to the engine by way of the line 36. Dirt separated from the fuel is trapped within the filter element 54 which may easily be replaced when required. As a result of this arrangement, vapor-free liquid fuel may be conducted by the line 36 to the engine under the effective propulsive force of the pump 16.

In the modification shown in FIG. 3, the upper portion or casting 18 is the same as in FIG. 1; but in this instance a different filter element 70 is provided. This element comprises a porous and fibrous cup-like filter 72, the rim of which is adhesively held to the periphery of a circular disc 74 which is smaller in outside diameter than the inner diameter of the cup 40 to present an annular flow space 76. The center of the disc 74 is apertured to receive the sleeve or wall 50 of the casting 18 and is so formed as to cooperate with a second disc 78 as to form a pocket 10 for retaining an O-ring 80. The latter bears resiliently against the outer surface of the sleeve or wall 50 to form a fluid tight seal. Two annular and contacting portions 81 and 82 of the discs 74 and 78 are joined together as by welding. The inner margin of the plate 78 is held in abutting relation with the shoulder 52, and its outer periphery cooperates with a ring 84 and a sealing washer 86 in holding the filter element 70 in position. An annular series of openings 88 are formed in the disc 78 to permit the passage of fuel to the space 76 and to the outside surface of the filter 72.

In the embodiment of FIG. 3 the function for removing vapor is the same as attained in the use of the apparatus of FIG. 1; but, because of the difference in the filter structure, sediment separated from the fuel is not retained by the filter element but is deflected thereby and drops to the bottom of the bowl 40 and is visible for inspection in the ascertainment of the necessity for cleaning the bowl.

It is to be understood that much of the vapor relieving characteristics of the separating devices obtain without inclusion of the filter, but the presence of the filter is preferred to secure an optimum performance in both vapor and dirt separation in a small unit. From this it may be seen that a separating device, with or without

a filter element, comes within the spirit of the present invention.

I claim:

5 A vapor separating unit for an internal combustion engine fuel system, said unit comprising a receptacle having an upper portion defining a U-shaped zone for receiving fuel vapor, a fuel inlet passage leading directly to an intermediate part of said U-shaped zone and an L-shaped liquid fuel outlet passage within said U-shaped zone, a lower portion of said receptacle defining a lower zone communicating and registering with said U-shaped zone for receiving liquid fuel from said fuel inlet passage, a part of said upper portion defining said L-shaped liquid fuel outlet passage including a depending sleeve extending 10 said outlet passage, a filter element surrounding said sleeve in said lower zone and arranged transverse to a flow path from said inlet passage to said outlet passage, an open vent of small flow capacity in said upper portion and leading from one leg of said U-shaped zone for removing vapor from said unit, and said inlet and outlet passages being of large flow capacity for handling liquid fuel.
